Patented May 4, 1920.

FIG. 1.

FIG. 2.

By

R. M. Wilson

Attorney

UNITED STATES PATENT OFFICE.

FRANK MAJEWSKI, OF CHICAGO, ILLINOIS.

DANCING-FIGURE TOY.

1,338,944.

Specification of Letters Patent.

Patented May 4, 1920.

Application filed August 14, 1919. Serial No. 317,600.

To all whom it may concern:

Be it known that I, FRANK MAJEWSKI, a citizen of Poland, residing at Chicago, in the county of Cook and State of Illinois, 5 have invented certain new and useful Improvements in Dancing - Figure Toys, of which the following is a specification.

The primary object of the present invention is to provide an improved construction 10 in figure toys in the embodiment of dancing dolls wherein there is provided a rotatable support for causing a circular progression of the dancing dolls while elements are caused to rotate within the circular support to cause a rotation of the dancing dolls 15 during the circular progression thereof.

A further object of the invention is to provide an improved figure toy that embodies a plurality of dancing dolls arranged 20 in couple formation with a novel form of operating mechanism for causing a main supporting disk to rotate with similar disks rotating therein, the device being manually operated.

25 With the above and other objects in view, the invention consists in the novel form, combination and arrangement of parts herein fully described in connection with the accompanying drawing and wherein like reference characters indicate similar parts throughout the several views.

In the drawing,

Figure 1 is a vertical cross sectional view of a figure toy constructed in accordance 30 with the present invention and

Fig. 2 is a bottom plan view of the cover removed showing the driving means for the small figure supporting disks.

Referring more in detail to the accompanying drawing, there is shown a casing 40 5 preferably rectangular in plan view having a bottom wall 6 and a removable top wall 7 secured thereto by fastening means passing through openings 8 formed in said 45 top wall 7.

A relatively large central opening 9 is formed in the top wall 7 and provides a clearance space for a rotating table top 10, the upper surface of which lies flush with 50 the upper surface of the top wall 7 as illustrated in Fig. 1, the same being supported upon the head 11 carried by the upper end of the shaft 12 that is rotatably supported at its lower end in the bearing stand 13.

55 As shown more clearly in Fig. 2, an angle bar 14 extends diagonally across the casing

with the angle ends thereof secured to the top wall as at 15 while a stationary disk 16 is secured thereto as at 17 and held immovable thereby, a central opening 18 being provided in the disk 16 through which the shaft 12 freely extends. The upper face of the disk 16 is cut away as illustrated in Fig. 1 to provide a clearance for the shaft head 11 and also a support for the bearing 60 plate 19, the upper face of which is provided with a race for ball bearings as illustrated, part of the weight of the rotatable table top 10 being supported on the ball bearings. The periphery of the disk 16 is 65 provided with a covering strip 20, the outer surface of which functions as a frictional element and the strip may be either a band of leather or sand paper, etc.

A plurality of circular recesses 21 are 70 formed in the upper face of the rotatable table top 10 and into which the disks 22 are adapted to be received, the disks supporting figures 23 as indicated in Fig. 1. Each disk 22 is provided with a central polygonal opening into which the squared end 24 of the shaft 25 extends, the shaft rotatably 75 extending from the adjacent portion of the table 10 and being supported in bearings formed in spaced bars 26 secured together 80 and to the under surface of said table top 10 by the fastening members 27, friction disks 28 being secured to the shafts 25 between the spaced bars 26 and in frictional 85 engagement with the band 20 upon the center stationary disk 16.

Means are provided for imparting rotary motion to the table top 10 and includes a crown gear 30 having a central hub portion 31 secured to the shaft 12 as at 32, the 90 crown gear 30 meshing with a pinion 33 secured upon the inner end of the shaft 34 horizontally journaled through the casing wall 5 and the bracket 35 while a crank handle 36 is secured upon the outer projecting end thereof.

In the operation of the device, rotary movement of the crank handle 36 through the meshing gear and pinion above described imparts rotary movement to the 100 shaft 12 and through the shaft to the rotatable table top 10. The disks 22 being carried by the table top 10 will rotate therewith and as the central disk 16 is held stationary by its connection with the angle bar 110 14, the small disks 28 meshing with the periphery of the central disk 16 will cause the

rotary motion of the disks 22 within the rotating table top 10 thus creating the impression of waltzing dolls by a revolving movement of the dolls through a circular progression thereof.

While there is herein shown and described what are believed to be the preferred embodiments of the invention, it is nevertheless to be understood that minor changes 10 may be made in the form, combination and arrangement of parts without departing from the spirit and scope of the invention as claimed.

What is claimed as new is:—

15 1. A figure toy embodying a casing, a cover wall removably attached thereto, an angle bar connected to the cover wall, a relatively large central disk secured to the angle bar, a shaft journaled through said 20 disk and supported at its lower end in said casing, the cover wall having a relatively large central opening therein, a rotatable table top received in said central opening and secured to the upper end of said shaft, 25 the upper face of said table top having a plurality of circular sockets therein, disks received in said sockets, figures supported on said disks, a shaft journaled through each socket of said table top and fixedly connected to the small disk disposed therein, disks upon the lower projecting ends of said shafts meshing with the periphery of the main disk, and means for rotating the shaft.

2. A figure toy embodying a casing, a 35 cover wall removably attached thereto, an angle bar connected to the cover wall, a relatively large central disk secured to the angle bar, a shaft journaled through said disk and supported at its lower end in said casing, the 40 cover wall having a relatively large central opening therein, a rotatable table top received in said central opening and secured to the upper end of said shaft, the upper face of said table top having a plurality of circu-

lar sockets therein, disks received in said 45 sockets, figures supported on said disks, a shaft journaled through each socket of said table top and fixedly connected to the small disk disposed therein, disks upon the lower 50 projecting ends of said shafts meshing with the periphery of the main disk, means for rotating the shaft, said means including a gear fixed to said shaft, a power shaft journaled in said casing, a pinion upon said power shaft in mesh with said gear and a 55 crank upon said power shaft exteriorly of said casing for operating the same.

3. A figure toy comprising a casing, a relatively large stationary disk centrally supported therein, a shaft journaled through 60 said disk, a rotatable table top fixed to the upper end of said shaft, disks rotatably supported in said table top, figures carried by said disks, friction wheels for operating said figure bearing disks frictionally engaging the stationary disk and means for operating 65 the shaft.

4. A figure toy comprising a casing, a relatively large stationary disk centrally supported therein, a shaft journaled through 70 said disk, a rotatable table top fixed to the upper end of said shaft, disks rotatably supported in said table top, figures carried by said disks, friction wheels for operating said figure bearing disks frictionally engaging 75 the stationary disk, a ball bearing connection between the table top and stationary disk and means for rotating said table top.

5. A figure toy comprising a casing, a 80 rotatable table top carried thereby, rotatable disks carried by the table top, a relatively large stationary disk within said casing, operative connections between the stationary and rotatable disks, and means for rotating the table top.

In testimony whereof I affix my signature.

FRANK MAJEWSKI.
